UNITED STATES PATENT OFFICE.

WILLIAM B. MOSES, OF BROOKLINE, MASSACHUSETTS, ASSIGNOR TO GRAY & DAVIS INC.,
OF CAMBRIDGE, MASSACHUSETTS.

IGNITION DEVICE.

1,262,544.

Specification of Letters Patent.

Patented Apr. 9, 1918.

Application filed March 10, 1916. Serial No. 83,257.

To all whom it may concern:

Be it known that I, WILLIAM B. MOSES, a citizen of the United States, and resident of Brookline, in the county of Norfolk and State of Massachusetts, have invented certain new and useful Improvements in Ignition Devices, of which the following is a specification.

This invention relates to ignition devices and with regard to certain more specific features thereof to so-called "timer distributor." It is one of the objects of the invention to provide an extremely compact device of the above mentioned character suitable for use in connection with multi-cylinder internal combustion engines.

It is another object of the invention to provide a reliable and efficient timer-distributor in which it is possible to obtain wide variation in spark timing, in which the parts may be quickly and conveniently assembled or disassembled and which will avoid confusion in attaching the leads from the spark plugs.

Other objects will be in part obvious and in part pointed out hereinafter.

The invention accordingly consists in the various features of construction, combinations of elements and arrangements of parts which will be exemplified by the construction hereinafter set forth and the scope of the application of which will be indicated in the following claims.

In the accompanying drawings wherein is shown the one of various possible embodiments of the invention,

Figure 1 is a view in elevation of an apparatus embodying the present invention, parts being broken away to more clearly disclose the interior construction.

Fig. 2 is a view in transverse section taken substantially on the line 2-2 of Fig. 1.

Fig. 3 is a view in top plan.

Fig. 4 is a vertical section taken substantially on the line 4-4 of Fig. 2.

Fig. 5 is a view in transverse section taken substantially along the line 5-5 of Fig. 4.

Fig. 6 is a side view of guiding means for holding certain of the movable parts against displacement.

Referring now more particularly to the drawings in which similar reference characters refer to similar parts throughout the several views, there is indicated at 1 a tu-

bular member having a shank 2 which serves as a shaft bearing and a cup or body portion 3 which serves as a casing for an interrupter mechanism to be presently described. The upper portion of the body 3 is flared or flanged at 4 to accommodate a distributor head indicated generally at 6.

Within the cup 3 there is mounted for angular adjustment a plate 7 which in turn has fixed thereon as by means of rivets 8, a pair of smaller plates 9 and 10. These smaller plates are separated from each other and insulated from the plate 7. A metal post 11 extends upwardly from the plate 9 and is in electrical communication therewith. This post serves as a pivot for a movable member or rocker 12 which in turn carries a contact point 13. The plate 10 is provided with a post 14 which supports a fixed contact 15. Primary circuit terminals 16 and 17 are kept respectively in constant electrical communication with the fixed and movable contacts mentioned by means of spring metal brushes 18 and 19 which bear respectively upon plates 9 and 10.

A shaft 20 is journaled in the shank 2 and is provided on its upper end with a contact actuating member in the shape of a cam 21 whereby the movable contact referred to is successively actuated to interrupt the primary circuit. The mechanism so far described is suitable for the requirements of 4 or 6 cylinder engines. To meet the demands of engines having a greater number of cylinders another movable contact member is mounted upon the post 11 and another fixed contact is provided on the post 14. A cam 22 is then fixed upon the shaft 20 in staggered relation to the cam 21 producing a general organization which compensates for electrical and mechanical lag and increases the life of the instrument. For details of this construction reference should be had to my co-pending application, Serial No. 72,496.

The distributor head comprises a terminal plate or cover 23 preferably of bakelite or some such insulating material. A common high tension terminal is provided centrally of this plate 23 as indicated at 24 and concentrically of this terminal are arranged the terminals for the leads to the different spark plugs of the engine. It will be noted that these latter terminals are arranged in two

different annular paths, terminals 25 being in the inner path with respect to the terminal 24 and the terminals 26 being outwardly located near the edge of the cover plate. By 5 such an arrangement it becomes possible to get, say, for instance, 12 terminals within a very small area and it is conceived that the arrangement would be more convenient and easier in assembly if these terminals 10 might be grouped in such a way that the leads would not intersect and result in confusion. The present invention is particularly adapted for use with V type internal combustion engines and may be positioned 15 between the V or at one end of the engine centrally of the V. As the ordinary timing of such engines calls for sparks alternately in cylinders on opposite sides of the engine, the present invention is adapted to group 20 the terminals so that the leads from the plugs on one side of the engine will come to one group of terminals and the leads from the plugs on the opposite side of the engine will come to another group of terminals. The 25 means used for obtaining this grouping will now be described:—

Mounted upon the flange portion 4 of the tubular member 1 and within the cover plate 23 is a contact supporting member or 30 frame 27. This member or frame is engaged by extensions of the posts 11 and 14 and is accordingly angularly movable conjointly with the plate or disk 7 and its appurtenances. The upper portion of frame 27 is 35 in the form of a plate or disk 28 and has fixed therein a plurality of contact pins 29, each of which is embedded in an elongated plate or strip 30 of brass or other suitable conducting medium. These plates and their 40 pins are arranged in two different annular paths similarly to the terminals on the cover plate and each terminal is provided with a spring pressed brush 31 adapted to bear on some portion of the strip 30 and 45 thereby maintain each pin 29 in electrical communication with the corresponding terminals 25 or 26. In this way an angular movement of the contact pins relatively to the terminals is permitted.

50 A contact carrying arm 32 of insulation is fixed upon the upper end of the shaft 20 to rotate with the cam member 21. A strip of contacting material 33 passes diametrically through said arm and provides contact points at either end one of which points coöperates with the contact pins of the inner annular row and the other of which coöperates with the contacts of the outer row. Extending upwardly from strip 33 is a flexible 55 conductor strip 34 upon which bears a brush 35 spring pressed from the terminal 24.

The under side of the body portion 3 of the tubular member 1 is provided with an arcuate slot 36 through which there extends 60 upwardly a pair of posts 37 and 38. These

posts engage the disk or plate 7 and one of them is provided with an extension which penetrates the frame 27. The arm 39 receives the lower end of these posts and is secured thereto in any suitable way, as by 65 means of nuts 40. The mechanism just described provides means whereby the operator may vary the positions of the various contact mechanism relatively to shaft 20 and to the terminal plate 23 and to the tubular 70 member 1. It is to be noted that the terminal plate is quick-detachable dependent upon manipulation of a spring latch shown in the drawings at the right in Fig. 4. A spring guide 41 bears upon the plate 7 at a point 75 substantially opposite the bearing points of the brushes 18 and 19 thereby preventing accidental displacement of the interrupter mechanism.

Provision has been made heretofore for 80 moving parts of the interrupter device relatively to the actuating means therefor in order to vary the time of the opening of the primary circuit with the ultimate result of advancing or retarding the time of sparking 85 in the engine cylinders. In order to compensate for this movement of parts in respect to the shaft which carried the actuating means, it has been necessary to elongate one of the contacting elements of the distributing device. Otherwise at the time the primary circuit would open the rotatable contact point might have passed entirely 90 beyond the contact point of the distributor head. The disadvantages of this elongated 95 contact construction have been obvious, and among them is the necessity for maintaining a large distributor head to accommodate the parts. The present invention obviates the necessity of elongating the contacts as 100 the terminal contacts are movable conjointly with the interrupter device.

In the operation of the distributor a secondary circuit is first completed through 110 an outer contact on one side of the head 110 and next through an inner contact on the opposite side and so on alternately for the entire rotation of the contact carrying arm. It is obvious, therefore, that the secondary circuit is completed alternately through terminals on opposite sides of the plate 23, thus permitting grouping 115 of the terminals as heretofore explained. It is, of course, to be understood that the contact pins 29 of one row are longer than the 120 contact pins of the other and that the oppositely disposed contact pins of the strip 33 lie in different horizontal planes to coöperate with the contacts of different rows.

The contact pins, points, et cetera, referred to in describing the distributor mechanism are of the type known as jump contacts. The invention, however, contemplates as well the use of wipe contacts or 125 any other form.

As many changes might be made in the above construction and many apparently widely different embodiments of the invention could be made without departing from the scope thereof, it is intended that all matter contained in the foregoing description or shown in the accompanying drawings shall be interpreted as illustrative and not in a limiting sense.

10 Having described the invention what I desire to secure by Letters Patent is:

1. In an ignition device, in combination, a distributor head comprising a common centrally arranged high tension terminal, an inner annular row of terminals concentric with the first said terminal and an outer annular row of terminals circumscribing said inner row, and means adapted to complete electrical circuits alternately through terminals of different rows comprising a distributor shaft, a contact member carried thereby and extending diametrically to coöperate alternately with terminals on opposite sides of said head and a contact electrically connecting said contact member with said common high tension terminal.

2. In an ignition device, in combination, a distributor head comprising a common centrally arranged high tension terminal, an inner annular row of terminals circumscribing the first said terminal and an outer annular row of terminals circumscribing said inner row, contacts in electrical communication with said terminals, and means adapted to complete electrical circuits alternately through terminals on opposite sides of said head.

3. In apparatus of the character described, in combination, a distributor head of insulating material, a terminal disposed centrally thereof, a plurality of terminals arranged in two annular paths concentrically of said first terminal, contacts extending from said terminals, and a rotatable member carrying substantially diametrically opposed contact points adapted alternately to coöperate with contacts of the different paths, said rotatable member having a third contact point coöperating with the contact extending from the first said terminal.

4. In apparatus of the character described, in combination, an interrupter device for a primary circuit, a distributing device comprising a rotatable contact member, contacts mounted for coöperation with said member, terminals engaging said contacts, and means adapted to vary the relative positions of parts of said interrupter device and in direct proportion to vary the relative angular positions of the rotatable member and contacts.

5. In apparatus of the character described, in combination, a casing having mounted therein a vertical timer cam shaft and interrupter contacts, a distributor head mounted

on said casing and comprising a cover plate having a plurality of terminals, each terminal having a contacting point, and a supporting member having a plurality of contacts adapted respectively to contact with contacting points of said terminals, and means for varying the relative angular positions of the cover plate and supporting member.

6. In apparatus of the character described, in combination, a casing having mounted therein a timer shaft cam and interrupter contacts and a distributor device associated with said casing comprising a cover plate having terminals, a rotatable contact carrying arm and an intermediate member supporting contacts in engagement with said terminals, said intermediate member being associated with said interrupter contacts for angular movement therewith whereby the positions of the contacts of the intermediate member and said interrupter contacts are varied relatively to said shaft.

7. In apparatus of the character described, in combination, a casing having mounted therein a timer shaft cam and interrupter contact means, and a distributor device associated with said casing comprising a cover having terminals, a rotatable contact carrying arm and an intermediate member being associated with said interrupter contact means for angular movement therewith whereby the positions of said contacts and said means are varied relatively to said shaft and said terminals, while still maintaining electrical communication between said contacts and said terminals.

8. In a timer-distributor, in combination, a shaft bearing having a cup shaped body, a shaft mounted therein, a plate arranged for angular movement in said body, fixed and movable contacts mounted on said plate, primary circuit terminals in said body having brush and plate connections with said fixed and movable contacts respectively, devices on said shaft for actuating said movable contacts, a distributor head comprising a terminal plate or cover of insulation fixed relatively to said shaft bearing and having a plurality of binding posts and a second member of insulating material mounted for movement with the first said plate and carrying a plurality of contacts in electrical communication by brush and plate with said terminals, and means whereby both of said contact carrying elements may be moved through an angular range relatively to the said shaft and the said shaft bearing and terminal plate.

9. In apparatus of the character described, in combination, a distributor device comprising a plurality of terminals and contacts extending in electrical communication from said terminals, a primary circuit interrupting device, and means whereby the said contacts may be moved relatively to said

terminals and the electrical communication maintained between each contact and its respective terminal.

10. In apparatus of the character described, 5 in combination, a distributor device comprising a plurality of terminals, contacts extending in electrical communication from said terminals and a rotatable contact carrying member adapted to coöperate with 10 said contacts to make and break the secondary circuits, a primary circuit interrupting device comprising a fixed contact and a

movable contact, a shaft having an actuator for said movable contact and carrying said rotatable contact carrying member, and means 15 whereby the terminal contacts may be moved conjointly with the contacts of said interrupting device and relatively to the said terminals.

Signed at Cambridge in the county of 20 Middlesex and State of Massachusetts this fourth day of March A. D. 1916.

WILLIAM B. MOSES.
